(57) CLAIM

The ornamental design for a pedal piano toy, as shown and described.

DESCRIPTION

FIG. 1 is a perspective view of a pedal piano toy showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the pedal piano toy that form no part of the claimed design. The dash-dot line is a boundary line and forms no part of the claim.

1 Claim, 7 Drawing Sheets
